CLARENCE E. PINK, OF CAMBRIDGE, MARYLAND

CONNECTER FOR WIRE FABRICS

Application filed August 29, 1931. Serial No. 580,197.

This invention relates to connecters for sectional woven wire belting and the like and of the character wherein the sections are alternately constructed from right and 5 left-hand coiled strands of woven wire to prevent creeping of the belt laterally when passing over curved surfaces such as conveyor pulleys or drums and said right and left-hand coiled strands when passing over 10 said surfaces develop within the fabric or belt internal strains due to the sections of the right-hand coiled strands creeping laterally in one direction while the sections of the left-hand coiled strands creep laterally 15 in the opposite direction, causing the various strains to localize where the sections are connected together; and the present invention has for the primary object, the provision of means for connecting the sections 20 together and capable of withstanding the strains and thereby preventing the belt or fabric from separating or tearing where the sections are connected.

Another object of this invention is the 25 provision of a connecter provided with relatively spaced closed loops or eyes, each of which is adapted to receive or have passed therethrough a convolution of the end right and left-hand coiled strands of adjacent sections so that said sections are prevented from 30 shifting laterally of each other and the coils or convolutions of the strands of adjacent sections are retained in alinement and not staggered as when secured together by connecters now in use.

A further object of this invention is the provision of a connecter constructed from a single length of wire bent upon itself to provide parallel side portions and having 35 the ends thereof secured together and the side portions twisted or braided with each other to provide the closed loops or eyes thereby providing a device capable of withstanding severe strains and which will last 40 over long periods of time.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a fragmentary plan view illustrating the sections of a woven belt or fabric of right and left-hand coiled strands of wire and the sections secured together by a connecter constructed in accordance with my invention,

Figure 2 is a similar view illustrating a modified form of my invention,

Figure 3 is a plan view of the connecter prior to being twisted or braided, and

Figure 4 is a similar view showing the 65 connecter completed.

Referring in detail to the drawing, the reference character 1 indicates a connecter for securing together sections 2 and 3 of a woven wire conveyor belt or fabric, wherein the section 2 is formed by woven left-hand coiled strands 4 and the section 3 of woven right-hand coiled strands 5 and as the end right and left-hand coiled strands of the sections cannot be woven together, the connecter 1 is employed for joining said sections.

The ends of the strands are looped together to provide a selvage 6 at each side edge of the belt or fabric. The sections thus formed prevent the belt or fabric from creeping laterally of a curved surface, and due to the construction internal strains are developed within the belt or fabric caused by the sections of the right-hand coiled strands having a tendency to creep laterally in one direction and the sections of the left-hand coiled strands to creep laterally in an opposite direction, and the internal strains are delivered to the connecters joining the sections and soon break or tear the conventional type of con-

necter now in use. The conventional type of connector also permits the sections to shift laterally of each other and with the internal strains acting with the lateral shifting of the sections render the conventional type of connector unfit for further use in a comparatively short length of time, also the conventional type of connector joins the sections so that the coiled strands of one section will be staggered or offset to the coiled strands of the adjacent section which places uneven strains on the connector; and to overcome the above-named disadvantages, my connector 1 is provided and consists of a single strand of wire 7 bent upon itself to provide parallel portions 8 connected by a bight portion 9. The side portions 8 are twisted or braided as shown in Figure 4 to provide spaced closed loops or eyes 10, each having a convolution or coil of the strands 4 and 5 of the sections 2 and 3 confined therein, thus holding them in alinement and preventing the sections from shifting laterally relative to each other. The ends of the wires 7 are then welded together or otherwise secured, providing a connector capable of withstanding severe strains and one which will prevent separation of the sections and will permit flexing between said sections.

50 By referring to Figure 1 of the drawing, it will be noted that the ends of the connector are positioned inwardly of the selvages of the belt or fabric and therefore are protected from wear, while in Figure 2 the connector passes through the looped ends of the strands which form the selvages; and in either form of my invention the necessity of securing the ends of the connector to the edges of the belt or fabric is obviated and as the ends of the conventional type of connector are connected to the ends of certain strands of the sections, they soon wear or tear, allowing separation of the sections and rendering the belt or fabric unfit for further use.

55 While I have shown and described the preferred embodiment of my invention, it will be understood that minor changes in construction, combination, and arrangement of parts may be made without departing from the spirit and scope of my invention as claimed.

Having thus described my invention, what I claim is:

1. A connector for joining sections of right-hand woven and left-hand woven wire belting, comprising an element bent to provide closed loops, said loops having convolutions of a coiled wire of adjacent sections therein to connect said sections and prevent lateral shifting of one section relative to another.

60 2. A connector for joining sections of right-hand woven and left-hand woven wire belting, comprising an element bent to provide relatively spaced closed loops and each

loop having a convolution of a coiled wire of each section therein to connect the sections and prevent lateral shifting of one section relative to another.

3. A connector for joining sections of right-hand woven and left-hand woven wire belting, comprising an element of a single length of material bent to provide relatively spaced closed loops and each loop having a convolution of a coiled wire of each section therein to connect the sections and to prevent lateral shifting of one section relative to another.

4. A connector for joining sections of right-hand woven and left-hand woven wire belting, comprising an element of a single length of material bent upon itself to provide parallel connected portions and said portions braided with each other to provide closed loops having the end strands of woven wire sections passed therethrough.

5. A connector for joining sections of right-hand woven and left-hand woven wire belting, comprising an element of a single length of material bent upon itself to provide parallel connected portions and said portions braided with each other to provide relatively spaced closed loops having the end strands of woven wire sections passed therethrough.

6. A connector for joining sections of right-hand woven and left-hand woven wire belting, comprising an element of a single length of material bent upon itself to provide parallel connected portions and said portions braided with each other to provide relatively spaced closed loops having the end coiled strands of woven wire sections passed therethrough, each loop receiving a convolution of each strand to maintain the sections from shifting laterally relative to each other.

7. A connector for joining sections of right-hand woven and left-hand woven wire belting, comprising an element of a single length of material bent upon itself to provide parallel connected portions and said portions braided with each other to provide relatively spaced closed loops having the end coiled strands of woven wire sections passed therethrough, said element having the free ends thereof welded or brazed together.

8. A connector for joining sections of right-hand woven and left-hand woven wire belting, comprising an element of a single length of material bent upon itself to provide parallel connected portions and said portions braided with each other to provide relatively spaced closed loops having the end coiled strands of woven wire sections passed therethrough, said element having the end portions thereof unattached with the side edges of the sections.

9. A connector for joining sections of right-hand woven and left-hand woven wire belting, comprising an element of a single

length of material bent upon itself to provide parallel connected portions and said portions braided with each other to provide relatively spaced closed loops having the end 5 coiled strands of woven wire sections passed therethrough, said element having the end portions thereof unattached with the side edges of the sections and arranged inwardly of said edges.

10 In testimony whereof I affix my signature.
